Primary Examiner—James M. Gandy
Attorney, Agent, or Firm—David L. King[57] **CLAIM**

The ornamental design for a tread for a tire, as shown and described.

DESCRIPTION

FIG. 1 is a perspective view of a tread for a tire showing my new design;

FIG. 2 is a front elevational view thereof;

FIG. 3 is a side elevational view thereof; and,

FIG. 4 is an enlarged fragmentary plan view of a portion of the tread as illustrated in FIGS. 1, 2 and 3.

The tread pattern is understood to be repeated uniformly throughout the circumference of the tread for a tire. The broken line showing of the tire sidewall in FIGS. 1 and 3 of the drawing is for illustrative purposes only and forms no part of the claimed design.
